LINK CHAIN FOR A BRACELET OR SIMILAR ARTICLE

Michael Chernow, New York, N. Y.

Application May 14, 1949, Serial No. 2,672

Term of patent 14 years

(Cl. D45—16)

To all whom it may concern:

Be it known that I, Michael Chernow, a citizen of the United States and residing at New York, in the county of New York and State of New York, have invented a new, original and ornamental Design for a Link Chain for a Bracelet or Similar Article, of which the following is a specification, reference being had to the accompanying drawing, forming part thereof, and in which:

Fig. 1 is a plan view of a link chain for a bracelet or similar article showing my new design,

Fig. 2 is a side elevation thereof, and

Fig. 3 is a perspective view of a section of the link chain shown in Figs. 1 and 2.

I claim:

The ornamental design for a link chain for a bracelet or similar article, substantially as shown.

MICHAEL CHERNOW.
